CAR DOOR OPERATING MECHANISM.

APPLICATION FILED JULY 6, 1914.

Patented June 6, 1916.

2 SHEETS—SHEET 2.

Fig. 5.

UNITED STATES PATENT OFFICE.

DAVID HINDAHL, OF CHICAGO, ILLINOIS, ASSIGNOR TO NATIONAL DUMP CAR COMPANY, A CORPORATION OF MAINE.

CAR-DOOR-OPERATING MECHANISM.

1,186,096.

Specification of Letters Patent.

Patented June 6, 1916.

Application filed July 6, 1914. Serial No. 849,206.

To all whom it may concern:

Be it known that I, DAVID HINDAHL, a citizen of the United States, residing at Chicago, in the county of Cook and State of Illinois, have invented certain new and useful Improvements in Car-Door-Operating Mechanism, of which the following is a specification.

This invention relates to improvements in car door operating mechanism, and has for its object to provide new and improved mechanism of the type described.

The main object of my invention is to provide an improved operating mechanism for actuating the dump doors of a car, this mechanism consisting in arms rotatably mounted upon a rotatable shaft pivotally connected at their extremities to other arms, in turn attached to the dump doors. In addition, I provide crank arms fixed to the rotatable shafts which coact with the first named arms to effect closing of the doors. These crank arms are also utilized to effect the initial movement from closed position of the actuating mechanism thereby permitting the doors to open and discharge the contents of the car. I further provide means attached to the car and coacting with the arms of the actuating mechanism to support the doors and their load in closed position. These and other objects will be set forth and more fully described in the following specification and shown in the accompanying drawings, in which;

Figure 1 is a side elevation of a portion of a car showing my invention applied thereto; Fig. 2 is a transverse section of a portion of a car showing a door in closed position; Fig. 3 is a view similar to Fig. 2 showing a door in open position; Fig. 4 is a detail of the shaft operating mechanism; Fig. 5 is a side elevation of a portion of the operating mechanism with the doors in closed position; Fig. 6 is a detail section along the line 6-6 of Fig. 2, the shaft being shown in elevation; and Fig. 7 a detail view showing the crank arm in elevation.

Like numerals refer to like elements throughout the drawings, in which—
10 designates generally a car having the side walls 11 attached to the side stakes 12, and further provided with the dump doors 13. Each of these doors 13 is provided with the bracket member 14 attached to the under side of said doors and projecting down-

wardly and outwardly therefrom at the front edge thereof, see Figs. 2 and 3, for example. Each of these brackets is provided with the slot 14^a in the lower portion and a rod or shaft 15 extends between these brackets and is normally seated in the slots 14^a, as shown clearly in Fig. 1. A rotatable operating shaft 16 is provided running longitudinally of the car at the side thereof, this shaft being preferably non-circular in cross section, as shown in Fig. 5. At suitable intervals along the shaft 16 are provided sleeves 17 apertured to closely fit the rods 16 and further secured thereto by means of bolts 18 or the like extending therethrough, see Fig. 6. 70 These sleeves are of circular periphery and have a portion thereof fitting in bracket bearings 19, bolted or otherwise secured to the stakes 12. This insures bearing of the shaft 16 such as will permit its easy rotation. 75

Carried by, and preferably formed integral with the sleeve 17, are the short crank arms 17^a having the hooked portion 17^a adapted to engage a thimble 20, see Figs. 2, 3 and 6. The crank arms 17^a are each provided with a cam face 17^b as indicated in Figs. 2 and 3 of the drawings. Rotatably mounted upon the sleeve 17 is the arm 21 formed of spaced apart strips 21^a, the same being inwardly bent adjacent their top portions, as viewed in Fig. 5, a pin 22 extending between said top extremities. The thimble 20 extends between the strips 21^a adjacent their mounting on the sleeve 17, this thimble 20 being held in position by the pin or rivet 90 23 and serving to maintain the strips 21^a in spaced relation as well as being arranged for engagement by the hooked portion 17^a of crank arm 17^a. Other arms 25 are provided, each being attached at one extremity 95 to the rod 15, and pivotally connected by means of the pins 22 to the arms 21 adjacent their other extremity, the arms 25 having their ends fitting between spaced apart strips 21^a, as shown in Fig. 5, for example. The 100 slots 25^a are provided at one end of each of the arms 25, the pins 22 extending through these slots 25^a to permit a slight amount of relative sliding of arms 25 with respect to arms 21. These arms 25 are provided with 105 cut-away portions 25^b forming shoulders 25^c, these shoulders being constructed with the rounded outer portion 25^d.

The operation of the structure described above is as follows: When the shaft 16 is 110

rotated in the proper direction, crank arm 17^a engaging thimble 20 will operate to move arms 21 toward the position shown in Figs. 2 and 5, the arms 25 being also moved toward this position, thereby effecting closing of the doors 13, as will be apparent. Prior to reaching the position shown in Fig. 2, the rounded portion 25^a of shoulder 25^c will engage a supporting roller 27 carried between angle brackets 28 which in turn are secured to the side wall 11 of the car. A continued rotation of the shaft 16 will result in the shoulder 25^c riding upon supporting roller 27, the slots 25^a permitting a slight amount of movement upwardly of arms 25 relative to arms 21. This results in the doors 13 being brought to tightly closed position, being supported in this position by means of arms 25 and supporting rollers 27.

At the same time the shaft being locked against reverse rotation, will prevent accidental opening of the doors. It will thus be seen that the load carried by the doors is directly supported by means of arm 25 and supporting rollers 27. I arrange and construct the mechanism so that when in closed position, as shown in Fig. 2, the center of support of arms 25 is approximately in vertical alinement with the center of the shaft 16; this arrangement also contributing to prevention of accidental movement of the mechanism from closed position. When it is desired to open or permit the opening of doors 13, a reverse rotation is imparted to the shaft 16, whereupon the outer cam face 17^b of the crank arm 17^a will contact with a face of the arm 25 at the cut-away portion 25^b and will operate to positively force the same from closed position permitting the door or doors to drop with their own weight and the weight of the load thereon, and requiring only a small torque to be applied to shaft 16 to effect or permit opening of the doors. To provide for rotation of the shaft 16, I attach the star or ratchet wheel 30 adjacent the end thereof. A sleeve 31 is mounted upon and attached to the shaft 16 adjacent the star wheel 30 and a socket member 32 is provided, this socket member having a ring portion 32^a rotatably mounted upon the sleeve 31. A pawl or dog 33 is pivotally attached to the socket member 32 and may be thrown into engagement with the star wheel 30 so that when a lever or handle is fitted in the socket member 32, proper oscillation thereof will result in rotation of the shaft 16, as will be apparent. A locking pawl 34, a portion of which is shown in Fig. 4, is provided to lock the shaft 16, when desired, against rotation from closing position.

It will be apparent from the above description that I have provided a new and improved car door operating mechanism.

While the embodiment shown and described

is susceptible of many modifications and changes, I do not wish to be restricted to such form beyond the scope of the appended claims.

What I claim is:—

1. In combination with a car having a dump door, a rotatable shaft, an arm operatively connected to said door, a second arm rotatably mounted upon said shaft and pivotally connected with said first arm, and means carried by said shaft to engage said second arm to effect closing of said door upon rotation of said shaft said means being arranged to coact with said first arm upon reverse rotation of said shaft to operatively move said arms from door-closing position. 70

2. In combination with a car having a dump door, an operating shaft, arms operatively connecting said shaft and door, and means carried by said shaft to engage one of said arms to close said door upon rotation of said shaft, and to engage another of said arms upon reverse rotation to positively move said arms from position closing said door. 80

3. In combination with a car having a dump door, an operating shaft, arms operatively connecting said shaft and door, and means carried by said shaft to engage one of said arms to close said door upon rotation of said shaft, said means being arranged to move another of said arms upon reverse rotation of said shaft to positively move said arms from position closing said door. 90

4. In combination with a car having a dump door, an operating shaft, an arm rotatably mounted upon said shaft and operatively connected to said door, said arm being provided with a pin member, and a crank arm carried by said shaft, said crank arm being arranged to engage said pin member upon proper rotation of said shaft whereby said first named arm will be operated to close said door. 100

5. In combination with a car having a dump door, a rotatable shaft, an arm rotatably mounted on said shaft, a second arm operatively connected to said door, said arms being operatively connected, and a crank arm carried by said shaft and arranged to operate said first named arm upon proper rotation of said shaft to effect the closing of said door and to operate said second arm upon a reverse rotation of said shaft to permit the opening of said door. 110

6. In combination with a car having a dump door, a rotatable shaft, an arm rotatably mounted on said shaft, a second arm operatively connected to said door, said arms being operatively connected, a crank arm carried by said shaft and arranged to operate said first named arm upon proper rotation of said shaft to effect the closing of said door, and a supporting member, one of 120

- said arms being arranged to coact with said member to support said door when in closed position.
7. In combination with a car having a dump door, a rotatable shaft, an arm rotatably mounted upon said shaft, a second arm operatively connected to said door and pivotally connected to said first named arm, a crank arm carried by said shaft and arranged to rotate said first named arm upon proper rotation of said shaft to close said door, said second named arm being provided with a portion lying adjacent said crank arm when said door is in closed position, and a supporting member, said second named arm being adapted to rest upon and be supported by said supporting member when in closed position.
8. In combination with a car having a dump door, a rotatable shaft, a sleeve member secured to said shaft, an arm rotatably mounted upon said sleeve member, said arm being provided with a pin, a second arm operatively connected to said door, said arms being pivotally connected, and a crank arm carried by said sleeve, said crank arm being adapted to engage said pin to rotate said first arm on proper rotation of said shaft.
9. In combination with a car having a dump door, a rotatable shaft, an arm rotatably mounted upon said shaft, said arm being constructed of spaced apart strips, a crank arm attached to said shaft and located between said strips, and a pin extending between said strips, said crank arm being adapted to engage said pin upon proper rotation of said shaft, said first named arm being operatively connected to said door.
10. In combination with a car having a dump door, a rotatable shaft, an arm rotatably mounted upon said shaft, said arm being constructed of spaced apart strips, a crank arm attached to said shaft and located between said strips, a pin extending between said strips, said crank arm being adapted to engage said pin upon proper rotation of said shaft, and a second arm operatively connected to said first named arm between said strips.
11. In combination with a car having a dump door, a rotatable shaft, an arm rotatably mounted upon said shaft, said arm being constructed of spaced apart strips, a crank arm attached to said shaft and located between said strips, a pin extending between said strips, said crank arm being adapted to engage said pin upon proper rotation of said shaft, and a second arm operatively connected to said door and pivotally connected to said first named arm between said strips.
12. In combination with a car having a dump door, a rotatable shaft, an arm rotatably mounted upon said shaft, said arm being constructed of spaced apart strips, a crank arm attached to said shaft and located between said strips, a pin extending between said strips, said crank arm being adapted to engage said pin upon proper rotation of said shaft, and a second arm operatively connected to said door and pivotally connected to said first named arm between said strips, said second named arm being provided with a cut-away portion to clear said crank arm when said door is in closed position.
13. In combination with a car having a dump door, door-operating mechanism comprising means for raising and lowering the door and a roller carried directly by the car independently of said means to support said door in closed position through the medium of said means.
14. In combination with a car having a dump door, door operating mechanism comprising an arm pivotally connected to the door and a roller carried by said car independently of said arm, said arm being arranged to rest on and be supported by said roller when said door is in closed position.

In testimony whereof, I have subscribed my name.

DAVID HINDAHL.
